(57) **CLAIM**

The ornamental design for an amplifier table, as shown and described.

DESCRIPTION

FIG. 1 is a front view of an amplifier table, embodying my new design;

FIG. 2 is right side view thereof;

FIG. 3 is a left side view thereof;

FIG. 4 is a rear view thereof;

FIG. 5 is a top view thereof;

FIG. 6 is a bottom view thereof;

FIG. 7 is a perspective view thereof; and,

FIG. 8 is an enlarged fragmentary view looking in the direction of arrows 8—8 of FIG. 2.
